SLIDING DOOR LOCK

Arthur R. Adams and Salvatore Merendino,
Pasadena, Calif.

Application June 23, 1954, Serial No. 31,117

Term of patent 3½ years

(Cl. D50—7)

Fig. 1.

Fig. 2.

Fig. 3.

Fig. 1 is a front perspective view of a sliding door lock, showing our new design;

Fig. 2 is a front elevational view thereof; and

Fig. 3 is a rear elevational view.

The characteristic features of the design reside in the portions shown in full lines.

We claim:

The ornamental design for a sliding door lock, as shown and described.
